UNITED STATES PATENT OFFICE.

AUGUST G. LIEBMAN, OF CHICAGO, ILLINOIS, ASSIGNOR TO VIGNOLE'S RAIL CHAIR COMPANY, OF NEW YORK, N. Y., A CORPORATION OF DELAWARE.

RAIL-CHAIR.

1,126,534.

Specification of Letters Patent.

Patented Jan. 26, 1915.

Application filed May 13, 1914. Serial No. 838,371.

To all whom it may concern:

Be it known that I, AUGUST G. LIEBMANN, a citizen of the United States, residing at Chicago, in the county of Cook and State of Illinois, have invented certain new and useful Improvements in Rail-Chairs, of which the following is a specification.

This invention relates to a railway track appliance and particularly to rail chairs.

10 The main object of the present invention is to provide a cheap rail chair so constructed that the rail may readily be adjusted laterally thereon and held in laterally adjusted position and also so formed that the 15 rail may be elevated upon shims.

A further object of the invention is to so form the base-plate of the chair that it may be readily and cheaply formed from a rolled section having an approximate form 20 of a channel-iron, the base plate being so formed as to provide oppositely disposed parallel abutments, these abutments being disposed at acute angles to the short axis of the base plate, as shown.

25 A further object is to provide a rail chair so formed that the chair will reinforce and support the screw spikes used therein by not only directly supporting the screw spikes but also by resisting lateral pressure or 30 thrust of the rail upon the screw spikes.

A further object of the invention is to so design the chair that it will be extremely simple and that very few pieces will be required to form the complete chair.

35 A further object of the invention is to so construct the chair that the rail may be adjusted without the necessity of removing or changing the primary fastenings holding the chair upon the tie.

40 Other objects will appear in the course of the following description.

The invention is illustrated in the accompanying drawings, wherein—

Figure 1 is a perspective view of a tie, a 45 rail and the improved rail chair thereon. Fig. 2 is a plan view of the construction shown in Fig. 1. Fig. 3 is an end elevation of the rail chair, the rail and a portion of the rail chair being in section.

50 Corresponding and like parts are referred to in the following description and indicated in all the views of the accompanying drawings by the same reference characters.

55 Referring to these drawings, A repre-

sents a rail having a standard cross section and B a tie supporting the rail.

Disposed upon the tie is a substantially rhomboidal bedplate 2 having a width approximately equal to that of the tie and 60 having upturned marginal flanges 3 at opposite ends. These flanges, as illustrated in Fig. 2, extend at an angle to the short axis of the bedplate and therefore at an angle to the rail A. The flanges are parallel to 65 each other. Disposed inward of the flanges 3 are the abutments 4. These abutments are spaced from the flanges but extend in the same direction and are parallel thereto. The abutments, as shown in Fig. 3, are higher 70 than the flanges 3. The bedplate 2 is held to the tie by means of the screw-spikes 5. Each screw-spike is formed intermediate its ends with a shoulder 6 designed to bear upon the upper face of the base-plate, and 75 below the shoulder 6 each spike is formed with wood screw-threads 7 for engagement with the tie. Above the shoulder 6, each spike is screw-threaded as at 8 for engagement with the nuts 9. These screw-spikes 80 are inserted between the flanges 3 and the abutments 4 as shown clearly in Fig. 2.

The rail A is held in place between the abutments 4 for lateral adjustment therebetween by the rail engaging members 10. 85 Each of these rail engaging members has a wedge-like portion which is disposed between the edge of the base flange of the rail and the corresponding abutment and also has a portion which extends over the base 90 flange 3, and a portion which extends over the corresponding abutment and through which each screw-spike passes.

In detail, each rail engaging member comprises a body portion 10 having a web 95 11 extending over the upper face of the rail base and a tapered wedging portion 12, the outer face of which bears against the adjacent face of the corresponding abutment and the inner face 13 bearing against the edge of 100 the rail base. From the body portion of the rail engaging member at its upper end extends outwardly a web 14 which is grooved as at 15 for the reception of the upper edge of the corresponding abutment. 105 This web 14 is adapted to bear upon the upper edge of the flange 3. The web 14 is longitudinally slotted as at 16, this slot extending parallel to the outer edge face of the web 14, this edge face being parallel to the 110

wall or flange 3. The spikes 5 extend loosely through the slots 16.

It will now be obvious that by shifting one of the rail engaging members in one direction and the other in the opposite direction, that the rail may be laterally adjusted and that the rail engaging members may be clamped tightly in wedging engagement with the rail and with the abutments 4. It will also be obvious that by shifting one of the rail engaging members in one direction and driving the other rail engaging member up, that the rail may be shifted upon the bedplate. Inasmuch as the space 15 between the abutments is relatively wide a maximum of lateral adjustment of the rail to gage may be accomplished.

The rail A may be vertically adjusted by inserting a shim or shims between the base 20 of the rail and the bedplate, one of these shims being indicated by the numeral 17. The spikes 5 project sufficiently above the base plate to permit nuts 9 to be turned up upon the portion 8 and thus permit of the 25 elevation of the rail clamping members. Of course, this elevation cannot be extreme without also placing a shim under the outer edge of the rail clamp between the rail clamp and the top of the short abutment or 30 flange. This will permit any required amount of vertical adjustment to the rail.

The object of providing the inner flanges 4 constituting the abutments is to brace the rail clamps against the lateral thrust of the 35 rail and resist any thrust directly to the spikes. The outer flanges 3 reinforce the shoulders 6 of the spikes and prevent any bending of the spikes by the thrust of the rail clamps. It will be seen that the rail 40 clamps extend over the flanges 3 and 4 and protect these flanges in case of derailment and also protect the spike. It is to be particularly noted in this case that by forming a length of channel-iron with the flanges 3 and 4, which structural element may be 45 readily formed by rolling, and then by cutting the channel-iron so formed at intervals diagonally to the side edges of the channel-iron, these base-plates or bedplates which 50 are provided with lateral flanges extending at an angle to the line of the rail supported upon the bedplate can be secured at a very reasonable cost. Thus it requires no special mechanism for the construction of these 55 bedplates other than the usual appliances in rolling mills and said bed plates may be constructed very cheaply. The rail clamps 10 may also be made of rolled material. The chair described has only three pieces 60 exclusive of the spikes and nuts. The adjustment of the wedging rail clamps may be easily accomplished by a section hand without the aid of any other tools except the ordinary trackman's wrench for adjusting the wedging clamps. Thus, it is an easy 65

matter to adjust the rails to gage. Inasmuch as in order to adjust the rails to gage and in order to shim the rails, it is not necessary to remove the primary fastenings of the rail chair, it is obvious that this adjustment of the rails may be made with a minimum of labor and without the necessity of removing or changing the primary fastenings.

One of the great objections to the present 75 method of holding rails to ties is due to the fact that any change in the adjustment of the rail requires respiking of the ties. As a consequence, these ties last but a relatively short time and soon become spike killed and 80 have to be renewed. It is for this reason that it is economically impracticable for railroads to use treated ties. These treated ties where they are not often respiked will last very much longer than the untreated 85 tie but the constant re-spiking of these ties renders them shortly of no value and they have to be renewed. The improved rail chair may be applied to a tie which would ordinarily be thrown away because of its being spike killed and sufficient additional life may be secured over a much spiked and 90 prematurely renewed tie to pay for the initial cost of the chair.

Having thus described the invention, what 95 I claim is:

1. In a rail chair, a base-plate formed at its extremities with upwardly extending flanges and inward of said flanges being formed with parallel abutments, the abutments and flanges extending parallel to each other but at an angle to the short axis of the base-plate, rail clamping members disposed upon said abutments and flanges, each member having a portion extending over the base flange of a rail and a wedging portion 100 extending between the base flange of the rail and the corresponding abutment, each wedging member having a portion bridging the space between the abutment and its corresponding flange, this portion being longitudinally slotted, and fastening devices passing through the base-plate and through said slots.

2. In a rail chair, a base-plate formed at its extremities with upwardly extending flanges and inward of said flanges being formed with parallel abutments, the abutments and flanges extending parallel to each other but at an angle to the short axis of the base-plate, rail clamping members disposed upon said abutments and flanges, each member having a portion extending over the base flange of a rail and a wedging portion 105 extending between the base flange of the rail and the corresponding abutment, each wedging member having a portion bridging the space between the abutment and its corresponding flange, this portion being longitudinally slotted, screw-spikes extending 110

through the base-plate and having a shoulder bearing thereon, each screw-spike extending up through the slot in the clamping member, and nuts engaging the upwardly projecting portions of the screw-spike.

3. A rail chair including a substantially rhomboidal base plate having spaced pairs of upstanding flanges of different heights, the inner flange of each pair constituting an abutment, rail clamping devices having wedging faces bearing against the inner faces of the abutments and provided with lips for engagement with the base of a rail, and fastening devices disposed between the flanges of each pair for holding the rail clamping devices in adjusted position.

4. In a rail chair, a base-plate having oppositely disposed parallel abutments and flanges extending parallel to said abutments, rail clamping members, fastening devices passing through the rail clamping members and the base-plate and disposed each in the space between an abutment and the corresponding flange, said fastening devices having heads bearing against the base-plate each having a width substantially equal to the space between the abutment and the flange.

5. A rail chair including a base plate having spaced pairs of upstanding flanges, one of the flanges of each pair being higher than the other and constituting an abutment, rail clamping devices having wedging faces engaging the abutments, and a fastening device disposed between the flanges of each pair and engaging the adjacent rail clamping device.

6. A rail chair including a base plate having spaced flanges of different heights, one of which constitutes an abutment, a rail clamping device bearing against the abutment and having a portion thereof extending over the adjacent flange, and means disposed between the flanges for holding the rail clamping device in adjusted position.

45 7. A rail chair including a base-plate having spaced upstanding flanges of different heights, one of which constitutes an abutment, a rail clamping device having a wedging face bearing against the abutment and provided with an extension adapted to rest on the upper edge of the adjacent flange, and means disposed between said flanges for holding the rail clamping device in adjusted position.

55 8. The combination with a rail, of a chair including a base plate having spaced upstanding flanges of different heights, one of which constitutes an abutment, the inner face of the abutment being disposed at an angle to the longitudinal edge of the rail, a rail clamping device having a wedging face engaging the inner face of the abutment and provided with a clamping lip for contact with the base of the rail, said rail clamping device being adjustable longitudinally of the

flanges and having a portion thereof adapted to bear against the outer flange, and means disposed between said flanges for holding the rail clamping device in adjusted position.

70 9. A rail chair including a base plate having spaced pairs of upstanding flanges, one flange of each pair being higher than the adjacent flange and constituting an abutment, rail clamping devices adjustable 75 transversely and vertically of the base plate and bearing against the abutments, said clamping devices being provided with slots, screw-spikes extending upwardly through the base plate between the flanges and projecting through the rail clamping devices, and nuts threaded on said screw-spikes and bearing against the rail clamping devices for holding said devices in adjusted position.

85 10. A rail chair including a base plate formed with spaced pairs of upstanding flanges, one of the flanges of each pair being higher than the other and constituting an abutment, rail clamping devices adjustable 90 transversely of the base plate and bearing against the abutments, said rail clamping devices being adjustable vertically of the abutments to permit the insertion of a shim between the outer flanges and the clamping 95 members, and means disposed between the flanges of each pair and extending through the adjacent clamping devices for holding the latter in adjusted position.

11. A rail chair including a base plate 100 having spaced pairs of upstanding flanges, the inner flange of each pair being higher than the outer flange and constituting an abutment, said abutments being disposed at an angle to the short axis of the base plate, rail clamping devices having grooves formed 105 in the lower faces thereof for the reception of the abutments, and means disposed between the flanges and engaging the clamping devices for holding said clamping devices in adjusted position.

110 12. The combination with a rail, of a chair including a base plate having spaced pairs of upstanding flanges, the inner flange of each pair being higher than the outer 115 flange and constituting an abutment, said abutments being disposed at an angle to the longitudinal edge of the rail, clamping devices bearing against the inner faces of the abutments and having their inner ends provided with lips for contact with the base of the rail and their outer ends provided with extensions adapted to rest on the outer flanges, and a fastening device disposed between the flanges of each pair and engaging 120 the adjacent rail clamping device for holding said rail clamping devices in adjusted position.

13. A rail chair including a base plate 125 having spaced upstanding flanges of differ-

ent heights, one of which constitutes an abutment, the inner face of said abutment being disposed at an acute angle to the short axis of the base plate, and a rail 5 clamping device having a wedging face for engagement with the inner face of the abutment and provided with a groove adapted to receive said abutment, said rail clamping device having an extension 10 adapted to rest on the outer flange, and a fastening device disposed between said flanges and engaging the rail clamping device for holding the latter in adjusted position.

15 14. The combination with a rail, of a chair including a base plate having spaced upstanding flanges of different heights, the inner flange being higher than the outer flange and constituting an abutment, the 20 inner face of the abutment being disposed at an angle to the adjacent longitudinal edge of the rail, a rail clamping member having a wedging face bearing against the abutment and provided with a straight 25 shoulder defining a lip for contact with the base of the rail, said rail clamping member being provided with an extension adapted to bear against the outer face of the abutment and the upper longitudinal 30 edge of the adjacent flange, respectively,

and means for holding the rail clamping member in position.

15. The combination with a base plate having spaced pairs of upstanding flanges of different heights, the inner flange of 35 each pair constituting an abutment, of a rail resting directly on the base plate or a shim between said pairs of flanges, screw-spikes extending through the base plate between each pair of flanges and having a 40 shoulder resting on the base plate and bearing against the flanges, rail clamping devices having wedging faces bearing against the inner faces of the abutments and provided with lips for engagement with the 45 base of the rail, said rail clamping devices being provided with extensions adapted to bear against the upper longitudinal edges of the short flanges and provided with slots adapted to receive the adjacent screw-spikes, and clamping nuts carried by the screw-spikes and engaging the adjacent rail clamping devices.

In testimony whereof I affix my signature in presence of two witnesses.

AUGUST G. LIEBMANN. [L. S.]
